UNITED STATES PATENT OFFICE.

EDWIN P. BENSON, OF NEW YORK, N. Y.

STUB BINDING AND ENVELOPE FOR CHECK BOOKS.

Application filed January 24, 1921. Serial No. 439,335.

To all whom it may concern:

Be it known that I, EDWIN P. BENSON, a citizen of the United States, residing at New York, in the county of New York and State 5 of New York, have invented certain new and useful Improvements in Stub Bindings and Envelopes for Check Books, of which the following is a specification.

This invention relates to a new and useful 10 system of arranging for the attachment to usual covers, of a collection of bank checks or the like, where a single stub-sheet serves for a plurality of checks arranged in vertical column and with a vertical edge of each ex- 15 tending from the edge of the corresponding stub-sheet. Heretofore the stubs of such check-sheets have been secured between the usual pasteboard covers by wiring through the fabric hinge which ordinarily connects 20 the covers. That is to say, the inner vertical edges of the stub-sheets were wired, with the result that it was difficult to hold the book open. Furthermore, these stub- 25 sheets have been provided on the front face with indicia pertaining to checks drawn, and have usually been ruled on the back for indicia pertaining to deposits, &c. With the old method of binding it has been very difficult to thus utilize the back of the stub, 30 because of the difficulty of holding back the stubs from which the check-sheets had been detached.

According to my invention I propose to secure the stubs to one cover or backing along 35 the upper horizontal edge, and utilize a part of each stub-sheet for indicia of deposits, &c., and the remainder of each stub-sheet, divided into sections corresponding in number to the number of checks attached to the 40 particular sheet, for indicia pertaining to those several checks. By reason of the fact that the stubs are secured to the back or cover at the upper horizontal edge, there is no difficulty in opening the book to lie flat, 45 and there is no occasion for turning back the stubs in order to write on the back of them, because provision is made for deposit indicia on the front; and even if it were desired to write on the back of the stubs, it is easier to 50 turn them back because they are held along an edge of least length. Furthermore, by wiring the sheets at the upper horizontal edge of the stubs I effect a considerable saving of paper.

55 I also contemplate utilizing in connection with the arrangement above referred to, a

permanent cover or envelope, in addition to the main covers or backing, which when the checks have all been detached will enfold the remaining collection of stubs for future reference or use, and I propose that this permanent envelope shall be wired to the stubs by the same wiring which unites them to the ordinary back or cover of the complete book. I also propose that this permanent 60 envelope shall carry the necessary indicia referring to the bank on which the formerly attached checks were drawn, with numbers, 65 dates, &c.

Other objects and aims of the invention, 70 more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are 80 to be taken as part of this specification, and in which I have shown merely a preferred form of embodiment of invention,

Figure 1 is a plan view of a check-book made up in accordance with my invention 85 and with the parts opened up;

Figure 2 is an edge view of the same;

Figure 3 is a perspective view illustrating the stubs after the checks have all been detached and the main cover or covers cut off;

Figure 4 is a perspective view of the subject-matter of Figure 3 with one fold of the permanent envelope turned down; and

Figure 5 is a similar view showing the envelope closed.

Referring to the numerals on the drawings, I show at 6 one of the usual main covers of a check-book and at 7 the other main cover or backing. These may be united by a hinge 8 of cloth or the like. Of course 100 it will be understood that I may use only one main cover or backing, for instance, the backing 7, omitting the cover 6 and the hinge 8. In any case, a collection or stack of stubs 9 is to be secured to the backing 7, and each stub will have attached thereto a plurality of checks 10, in vertical column as shown in Figure 1, these checks being separable from their corresponding stub, and from each other along weakened lines 11, in 105 the usual way. Each stub preferably has a part, for instance, the upper part thereof,

provided with the necessary ruling and indicia for the entry of facts and data relating to deposits, and another part, for instance, the lower part thereof, on which will be 65 carried rulings and indicia relating to the several checks attached to the particular stub, and to balances, &c. The collection or stack of stubs may be secured to the backing 7 as by means of sewing or wiring 12, which 70 unites the upper horizontal edges of the stubs to the upper horizontal edge portion 10 of the backing 7.

If desired, I may also provide an envelope 15 for the stubs, which may be of paper or other material and comprising a back 14 to lie underneath the collection of stubs, integral end folds 15 and 16 to go over the horizontal edges of the stack, and cover folds 20 17 and 18 to go over the front of the stack, cover fold 18 having an aperture or eyelet 19 for engagement with a prong fastener 20 carried by the other cover fold. The wiring or 25 stitching 12 will pass through the back 14 of the envelope along the upper horizontal edge thereof, as well as through the horizontal edge of the stack and of the main backing 7. After the checks have all been used up, the 30 main backing 7 is cut off along a line corresponding with the right-hand edge of the stack or of the envelope in Figure 1; and if the other main cover 6 and hinge 8 are also present, these are also removed by cutting through the hinge along the line of the left-hand edge of the stack in Figure 1. Thereupon, 35 the envelope may be closed about the stubs as shown in Figures 3, 4 and 5. Preferably, the envelope will carry indicia relating to the contained stubs, as for instance the name of the bank on which drawn, the inclusive 40 numbers of the checks, and the inclusive dates thereof, and if desired also the name of the drawer of the checks. Such indicia may be conveniently be carried on one of the end-fold portions 15 or 16, so that the 45 envelopes may be filed away on edge with the indicia exposed.

Until such time as the checks have all been used up, the cover folds 17 and 18 of the envelope may lie between the main backing 7 and the bottom of the stack of stubs, being 50 bent towards each other along the lines 21—22 of Figure 1. Or to make a more sightly article, these two folds 17 and 18 may be folded upon themselves along the 55 lines 23—23 and then folded upon each other and upon the backing 7, along lines corresponding with the horizontal edges of the book; in which case no portions of the envelope will project appreciably beyond the 60 horizontal edges of the book.

While I have spoken of bank checks in particular, it is to be understood that the invention is equally applicable in connection with other forms, such as drafts, receipts, or

the like, and I intend no limitation whatever 65 by the use of the word "checks" or by referring to indicia of deposits, &c.

Inasmuch as many changes could be made in the above construction, and many apparently widely different embodiments of my 70 invention could be made without departing from the scope thereof, it is intended that all matter contained in the above description or shown in the accompanying drawings shall 75 be interpreted as illustrative and not in a limiting sense.

It is also to be understood that the language used in the following claims is intended to cover all the generic and specific features of the invention herein described and all statements of the scope of the invention which, as a matter of language might be said to fall therebetween.

I claim:—

1. A device of the kind described, comprising a stack of stub-sheets and attached checks, each stub-sheet having detachably connected thereto a plurality of check-forms in vertical column, each stub-sheet having thereon indicia relating to bank deposits and also distinct indicia relating to the respective check-forms pertaining thereto, an envelope having a back co-extensive with the stub-sheets, edge-fold portions co-extensive with the thickness of the stack of stub-sheets and cover portions for covering the front of the stack of stub-sheets, a main backing underlying the stack of stub-sheets and checks and the envelope back and parallel thereto, and fastening means passing through the horizontal edge portions of the stack of stub-sheets and through the upper edge portion of the envelope back and of the main backing.

2. A device of the kind described, comprising a stack of stub-sheets and attached checks, each stub-sheet having detachably connected thereto a plurality of check-forms in vertical column, each stub-sheet having thereon indicia relating to bank deposits and also distinct indicia relating to the respective check-forms pertaining thereto, an envelope having a back co-extensive with the stub-sheets, edge-fold portions co-extensive with the thickness of the stack of stub-sheets and cover portions for covering the front of the stack of stub-sheets, means for securing the cover portions together, a main backing underlying the stack of stub-sheets and checks and the envelope back and parallel thereto, fastening means passing through the horizontal edge portions of the stack of stub-sheets and through the upper edge portion of the envelope back and of the main backing, and indicia relating to the stubs on one of the edge-fold portions of the envelope.

In testimony whereof I affix my signature.
EDWIN P. BENSON.
